PHONOGRAPH RECORD HOLDER

Seymour Robins, New York, N.Y.

Application March 26, 1946, Serial No. 657,098

7 Claims. (Cl. 312—10)

1

This invention relates to improvements in containers or holders; and more particularly a holder for phonograph records of the circular disk type, having a sound track on one or both faces thereof.

An object of the invention is to provide a holder comprising two separable sections for receiving and enclosing the records when they are to be stored or put away for further use; and further so constructed that one of the sections can be set up and made to serve as a convenient support for maintaining the records in exposed and accessible positions; so that they can be displayed, examined, and easily removed and transferred to a sound reproducing apparatus for operation.

Another object of the invention is to provide a holder in which the records can be placed without contact between the holder and their surfaces; and by which they can be similarly set up and exposed so that they can be grasped by hand only on their edges. Thus surface handling and the like are eliminated and risk of impairment of the sound track is obviated.

A further object is to provide a holder of this type which also has means for snugly and tightly securing the phonograph disks within it, so that shaking and jarring are prevented and risk of breaking obviated.

The nature and advantages of the improvement are fully described in the ensuing specification; and the novel features are pointed out in the appended claims. But this disclosure is illustrative only, and in practice many changes in details may be adopted without deviating from the principle of the invention or exceeding the scope and meaning of the terms in which the claims are expressed.

On the accompanying drawings:

Figure 1 is a perspective view of the rear of a record holder according to this invention.

Figure 2 is a section on line 2—2 of Figure 1.

Figure 3 is a section on line 3—3 of Figure 2.

Figure 4 is a section on line 4—4 of Figure 3.

Figure 5 is a rear perspective view of part of the holder when set up as a support for the records to keep them in position for immediate use.

Figure 6 is a vertical section taken through the middle of Figure 5; and

Figure 7 shows a modification of the holder.

The same numerals identify the same parts throughout.

The holder is shown as comprising two main parts or sections, an upper 1 and a lower 2. A stud or pin 3 with a head at one end engages the holder in such a way as to pass through from front to back; and when the records are inside

2

this stud also penetrates the central apertures of said records by which they are centered on the revolving platen of the sound reproducing apparatus when placed in playing position. By means of this pin the disks are secured or bound against movement in the holder, and the sections 1 and 2 are retained in engaging relation; so that the disks are completely encased by the sections 1 and 2.

Inside the upper section 1 are spacers 4, between which are ribs 5, which project inward slightly with respect to the spacers 4. The general shape of the holder is presented as square; and the spacers 4 fit the corners at the top of the section 1 on both sides. Both the spacers and the ribs have the same general curvature as the circumference of the disks; and the lower section 2 has complementary spacers 6 with intervening, slightly projecting ribs 7 which match or register with the ribs 5. The upper section 1 is larger than the lower, enveloping more than half of each phonograph record disk 8. Therefore the ribs 5 are of considerably greater extent than one half the circumference of the disks 8, while the lower ribs 7 are less than half the circumference. The upper ribs 5 follow the curvature of the edges of the disks 8 over most of the extent of said edges, but diverge a little as indicated at 9 adjacent the open end of the upper section, which fits upon the lower section 2. This feature makes the spaces between the spacers 4 at the open end of the section 1; which appears as the lower end in Figure 5, of greater width than the diameter of the disks; so that the disks can be more easily inserted or received in the upper section in the several pockets between the ribs 5. In the lower section, the ribs 7 follow the curvature of the disks 8 over the entire extent of that portion of the disks which is contained within the lower section.

The top of the lower section 2 is open, like the lower end of the upper section 1; the opposite ends of the two sections being closed, as are the sides of both sections. The meeting edges of the two sections are rabbeted, as depicted at 10. When the holder is closed, the edge of the top section 1 telescopes into the engaging edge of the lower section 2 and makes a snug fit with the latter.

The sections 1 and 2 may be of cardboard or other fibrous material; or plastic or other suitable substance. The ribs 5 and 7 can be of almost any non-metallic material, and clamped firmly between the spacers 4 and 6 respectively.

The surfaces with the sound tracks of the disks

8 in the holder never come into contact with one another, or with any part on the inside of the holder. They engage the ribs only along their edges, and are kept apart by the ribs 5 and 7.

When the records are not needed, the holder is closed, as shown in Figures 1 and 2. To get the records ready for use, the top section is removed, exposing the greater part of these records, but leaving them enveloped over their lower portions, as appears in Figures 5 and 6. In this position, the section 2 is set up as a stand or support; in a manner now to be explained; so that the records can be lifted out and disposed in a machine to reproduce audibly the material etched thereon.

To enable the section 2 to serve the purpose of a stand or support, it is equipped with a prop or leg 11 at the back. This prop is hinged to the upper edge at the rear by a suitable element 12, which is preferably a piece of strong cloth or other fabric, attached to the section and the prop or leg 12 by adhesive or other suitable means. This leg or prop is of the same material as the sections 1 and 2. It is rounded at its outer end, and when the holder is closed, this member or leg 11 fits into a suitable opening in the rear of the upper section 1, and is flush with the outer surface thereof. It has the same thickness as the walls of the holder along its longitudinal edges and free end; but from a point near the free end to the edge engaged by the hinge 12, the thickness is reduced to make a recess or depressed seat 13 on the outer face of this member to receive a flap 15 hinged by a piece of stout cloth glued in place or by other means to the outer end of the member 11, and upon the outer face of same. The hinge 12 is U-shaped, with arms that project upward from the edge of the section 2, and these arms are affixed to the thicker sides of the member 11. When the sections 1 and 2 are connected, the catch 15 lies in the recess 13, fitting snugly in this recess between the sides 14 thereof, and is flush with the outer faces of the sides of the member 11. The free end of this flap is rounded, so that by means of any suitable implement inserted into small spaces at the corners of the U-shaped hinge, this flap can be released and swung outward.

Hence, when the lower section is set up as a stand, with the upper section removed, the flap is freed and the member 11 pulled down into the position shown in Figure 6. The flap is disposed under the section 2, with a projection 18 which it carries under the lower rear edge of section 2. This projection abuts against the inner end of a recess 20 in the bottom of the section 2. Thus the section 2 is prevented from slipping. The disks 8 are held snugly at their lower portions in the pockets of the section 2 between the ribs 7; but can be lifted out quite readily.

When the holder is closed it can be locked shut by the stud 3 and the member 11. The stud is mounted in the member 11, and is exposed through an aperture 17 in the flap 15 when the latter is laid in the recess 13. When the upper section is fitted upon the lower, the flap 15 is laid against the outer face of the member 11, its projection 18 being first liberated from the recess 20; and then the member 11 is swung up into the recess 13 provided in the rear face of the section 1. It fits this opening snugly and the projection 18 now enters a slot or recess 19 in the member 11. Finally the stud or pin 3 passes through the central aperture in the disks 8 and engages an aperture in the front of the section 1. This re-

cess and the end of the stud may be threaded, to enable the stud to be virtually locked, or it merely may have a sufficiently tight fit. The disks are now held securely and cannot be moved or shaken in the holder; and they can be extracted by merely withdrawing the stud 3 which is exposed at opening 17 in the flap 15, and separating the top section from the lower section. The stud 3 and member 11, with the flap 15, thus keep the holder closed and serve the additional function of propping the section 2 in required position when the records 8 have to be taken out of the holder.

In another form of my holder, the spacers 4 and 6 with their ribs 5 and 7 may be each made in one piece, as indicated in Figure 7. The spacers will then have the shapes shown at 4' and 5' in Figure 7 and the ribs will be integral therewith.

The holder can be made large enough for a good many records and the surfaces with the sound tracks thereon are protected as stated above. In the holder only the parts on or near the circumference of the records are ever in contact with anything and this is also true when the part 2 is used as a support to display the records. To remove them from the holder 2 when the latter is set up as in Figure 6 the records have to be grasped at the circumference only.

Thus my improved record holder is admirably adapted to serve both as a container for records to receive and enclose them or as a stand or support to be put up in a store for display or upon a table or the like close to a sound reproducing machine, and transferred to the machine to be played at will. The construction of the holder is strong, but the general design is simple, and the lower section is well propped when needed as a support; and the disks are tightly enclosed when the holder is shut to protect them against jars and jolts that would otherwise entail breakage and other injuries.

Having thus described my invention, what I claim is:

1. A holder comprising two detachable parts having inside ribs defining pockets, the ribs of one part being in alignment each to each with those of the other to receive disks to be inserted in said pockets, said parts being shaped to fit together along a line intersecting said disks, a member carried by one of said parts and securing means carried by said member to engage said disks and the other part of said holder.

2. A holder having ribs affixed to its interior, the ribs defining pockets between them to receive the edges of disks bearing sound tracks, said holder comprising parts, one of which has a hinged member, and securing means carried by the member to engage said disks and the other part of the holder to hold the disks motionless therein.

3. A holder comprising two detachable parts having inside ribs defining pockets, the ribs of one part being in alignment each to each with those of the other to receive disks to be inserted in said pockets, said parts being shaped to engage along a line transverse to said disks and a member hinged to one part and having projecting means to engage said disks to keep them motionless in said holder, said means also engaging the other part of the holder to connect said parts together.

4. A holder for phonograph records of disk form comprising an upper and a lower section

containing pockets for the records, each of said sections containing parts of each pocket, said sections being separable from one another so that the upper section can be detached, leaving the records exposed in the lower section, a movable member attached to the lower section for propping the lower section in inclined position and securing means carried by said member to engage said disks and the upper section to hold said sections and said disks.

5. A holder for phonograph records of disk form comprising an upper and a lower section containing pockets for the records, each of said sections containing parts of each pocket, said sections being separable from one another so that the upper section can be detached, leaving the records exposed in the lower section, a movable member attached to the lower section for propping the lower section in inclined position, said member having a hinged flap with a projection to engage the bottom of the lower section to retain said member in proper position.

6. A holder for phonograph records of disk form comprising an upper and a lower section containing pockets for the records, said sections being separable from one another so that the upper section can be detached, leaving the records exposed in the lower section, and means for propping the lower section in inclined position comprising a member having a flap to engage the bottom of the lower section to retain said member in operative position, said member being hinged to the upper rear part of the lower section, the flap being hinged to said member, the latter having a recess between its edges to receive and seat the flap, and the adjacent part

of the upper section having a recess into which said member fits and becomes flush with the outer face of said holder.

5 7. A holder for phonograph records of disk form comprising an upper and a lower section containing pockets for the records, said sections being separable from one another so that the upper section can be detached, leaving the records exposed in the lower section, and means for propping the lower section in inclined position comprising a member having a flap with a projection to engage the bottom of the lower section to retain said means in operative position, said member being hinged to the upper rear part of the lower section, the flap being hinged to said member, the former having a recess between its edges to receive and seat the flap and the adjacent part of the upper section having a recess into which said member fits and becomes flush with the outer face of said holder, said member carrying a pin to penetrate the disks, and the opposite face of the holder having an aperture to receive the pin.
